CLAIM

The ornamental design for a printer cassette, as shown and described.

DESCRIPTION

FIG. 1 is a top, front, left-side perspective view of a printer cassette in accordance with our new design;

FIG. 2 is a front elevation view of the printer cassette shown in FIG. 1;

FIG. 3 is a rear elevation view of the printer cassette shown in FIG. 1;

FIG. 4 is a right-side elevation view of the printer cassette shown in FIG. 1;

FIG. 5 is a left-side elevation view of the printer cassette shown in FIG. 1;

FIG. 6 is a top plan view of the printer cassette shown in FIG. 1; and,

FIG. 7 is a bottom plan view of the printer cassette shown in FIG. 1.

The dash-dash broken lines immediately adjacent the shaded area and the dash-dot-dash broken lines on the tab represent the bounds of the claimed design while all other dash-dash broken lines illustrate portions of the article that form no part of the claimed design. The dash-dash broken lines and the dash-dot-dash broken lines form no part of the claimed design.

1 Claim, 6 Drawing Sheets
